UNITED STATES PATENT OFFICE.

PETER HARNIST, OF MARINE, ILLINOIS.

FLOUR-MILL FEEDER.

SPECIFICATION forming part of Letters Patent No. 290,421, dated December 18, 1883.

Application filed September 15, 1883. (No model.)

To all whom it may concern:

Be it known that I, PETER HARNIST, of Marine, in the county of Madison and State of Illinois, have invented certain new and useful Improvements in Flour-Mill Feeders, of which the following is a full, clear, and exact description.

Reference is to be had to the accompanying drawings, forming part of this specification, in which similar letters of reference indicate corresponding parts in all the figures.

Figure 1 is a sectional front elevation of my improvement. Fig. 2 is a sectional side elevation of the same, taken through the line $x-x$, Fig. 1. Fig. 3 is a plan view of the same, the cover being removed. Fig. 4 is a sectional side elevation of a modification of the same.

The object of this invention is to secure uniformity in feeding flour, middlings, grain, and other substances to sieves and rolls in flour-mills.

A represents the box or casing of the feeder, in the top of which is an aperture, in which is secured the end of a spout, B, for introducing the substance into the feeder.

To the upper part of the rear side of the casing A is hinged, by staples D or other suitable means, the upper edge of a plate, E. The lower part of the plate E rests upon crank-arms G, formed upon or rigidly attached to a shaft, H, which works in bearings in the sides of the casing A, and has a crank, I, formed upon or attached to its end for convenience in operating it, so that by operating the crank-shaft H any desired inclination can be given to the plate E. The crank-shaft H can be secured in any position into which it may be adjusted by pins J, designed to be inserted in holes in the side of the casing A at the sides of the crank I.

To the upper part of the plate E is attached a spout, K, to receive the substance from the spout B and guide it to the semi-conical plate L, attached to the said plate E, and by which the said substance is spread into a sheet as it passes down.

To the casing A are attached two inclined plates, M, to receive the substance, contract it into a thin sheet, and feed it to the sieves or rolls C of the mill.

In the upper part of the casing A, in front of and facing the spout K, is placed a second spout, N, to assist in guiding the substance to the spreader L. The spout N is supported from the casing A or plate E by wires or rods O, to which the said spout N is attached.

If desired, a second inclined plate, E', can be placed below the plate E, and in a reversed position, the said plate being provided with a spreader, L', and an adjusting crank-shaft, G' H', in the same manner as the first plate E, as shown in Fig. 4.

With this construction the flour, middlings, grain, or other substance will be fed to the sieves or rolls in a wide thin sheet, so as to be evenly distributed.

Having thus described my invention, what I claim as new, and desire to secure by Letters Patent, is—

1. In a feeder, the combination, with the casing, of the inclined plate having at its upper end the guide-spout K, and below said spout the semi-conical spreader, the guide-spout N, arranged to extend within the guide-spout K, and the inclined guide-plates M, substantially as and for the purpose set forth.

2. A feeder, constructed substantially as herein shown and described, consisting of a casing, an inclined plate provided with a guide-spout, a semi-conical spreader, an adjusting crank-shaft, and a pair of inclined guide-plates, as set forth.

3. In a feeder, the combination, with the guide-spout K and the adjustable inclined plate E, of the guide-spout N and the semi-conical spreader, as set forth.

PETER HARNIST.
